UNITED STATES PATENT OFFICE.

WILLIAM G. LIEBIG, OF DETROIT, MICHIGAN.

SUPPORTING-BLOCK FOR BRUSH-BACKS.

1,119,023.

Specification of Letters Patent.

Patented Dec. 1, 1914.

Application filed February 9, 1912. Serial No. 676,658.

To all whom it may concern:

Be it known that I, WILLIAM G. LIEBIG, who am a citizen of the United States of America, residing at Detroit, in the county of Wayne and State of Michigan, have invented certain new and useful Improvements in Supporting-Blocks for Brush-Backs, of which the following is a specification.

10 This invention relates to devices for supporting brush backs in position, both while the tuft holes are being bored therein, and when the insertion of the tufts is subsequently begun, and has for its object an improved device of this type adapted especially for brush backs of partly straight and partly circular cross-sectional outline, wherein the location of the tuft holes and consequently of the bristles, is in the straight 20 or plane side, and which would otherwise be difficult to support against rocking when resting on the curved side.

In the drawings:—Figure 1 is a perspective of the device, with a brush back in position thereon. Fig. 2 is a cross section on the line $x-x$ of Fig. 1. Fig. 3 is a cross section on the line $y-y$ of Fig. 1.

A represents the base of the block, at each end of which is located a rest B, whose top 30 is of about the curvature of the brush back that is to be handled, or of a slightly greater curvature. This block may be in one piece or two parts between which the metal block D is inserted. In these rests, and extending 35 above the central portion of the base A, is placed the block C, in which are first to be bored the tuft-holes E, in which, in a later step in the operations, are to be set the tufts of bristles.

40 In the center portion of the base D are located the pivoted claws F, whose outer ends are adapted to engage in the previously bored handle holes E in the center of the brush back C. The lower ends H of the claws, below their points of pivoting, are adapted to be engaged by the upper end of the screw J, which is preferably operated from the under face of the block, so as to force the outer points of the claws toward 45 one another, and consequently into the holes, 50

in the brush back C, thus holding it firmly against the curved top portions of the rests B, and against rocking, even when the force of the boring member or the tuft-setting member is directed against holes in the row 55 nearest either edge of the plane face of the blank. Since the center of the curved face of the blank illustrated is at the point K, it is evident that, except for the support 60 against rocking given the blank by this device, any pressure on its upper plane face except on the row of holes exactly in its center would cause the blank to rock most objectionably; and this would be true even were the cross section of the blank less than 65 a segment whose chord is located on the same side of the center as the curved periphery.

It is of course within the scope of my invention to use two actuating screws, one for 70 each pivoted claw member, and located either in the bottom of the base or in its side, but the type illustrated is far preferable.

What I claim is:—

1. A supporting block for brush backs, comprising a body portion having a relatively low center portion and raised ends having their upper surfaces longitudinally rounded, a pair of pivoted claw members 80 located in said low center portion in position to engage previously bored holes in the corresponding portion of a blank, and a screw member whereby said claws may be caused to open and close with respect to 85 said bored blank, substantially as described.

2. In combination with a supporting block having its end portions shaped to receive a blank laid therein, a pair of claw members pivotally supported in the central portion 90 of said block in position to engage the corresponding portion of the blank, and means for causing the opening and closing movement of said claws with respect to one another and to the blank, substantially as described.

3. In a supporting block for brush backs, in combination with a supporting member having its ends fashioned to engage partially about a blank laid thereon a pair of 100

claw members attached to the intermediate portion of the supporting member and a controlling screw adapted to engage said claw members whereby their position with respect to the blank may be regulated, substantially as described.

In testimony whereof I affix my signature in presence of two witnesses.

WILLIAM G. LIEBIG.

Witnesses:

WILLIAM M. SWAN,

JEFFERSON G. THURBER.
